Frederick Gale.

UNITED STATES PATENT OFFICE.

FREDERICK GALE, OF LANCEFIELD, VICTORIA, AUSTRALIA, ASSIGNOR OF
ONE-THIRD TO THOMAS ARNOLD PARKS, OF ROMSEY, AUSTRALIA.

TOY GUN.

SPECIFICATION forming part of Letters Patent No. 757,292, dated April 12, 1904.

Application filed October 26, 1903. Serial No. 178,605. (No model.)

To all whom it may concern:

Be it known that I, FREDERICK GALE, a subject of the King of Great Britain and Ireland, residing at Lancefield, in the State of Victoria, 5 Commonwealth of Australia, have invented certain new and useful Improvements in Toy Guns; and I do hereby declare the following to be a full, clear, and exact description of the invention, such as will enable others skilled in the art to which it appertains to make and use the same.

This invention originated in an effort to extend the applicability and popularity of one of the most delightful and yet harmless of 15 toys, the pop-gun. That article appeals only to very young children as a rule, for its explosion or "pop" is faint, and its cork plug, being usually tied to the piston or barrel, serves no purpose except to help cause the explosion, 20 such plug acting, therefore, as part of the gun, the cord saving time in replacing the plug and preventing its being lost. Though attaching and using the plug as part of the pop-gun or the like, this invention comprises 25 improvements whereby the toy is made pleasurable not only to young children, but also to those of more advanced age, and adapted to afford amusement to adults individually or in a parlor-game, as it allows of the discharge 30 at will of darts, peas, and shot for target-practice and enables the application of personal skill.

Other novel features are set forth below.

The drawings represent parts of a pop-gun 35 embodying this invention, Figure 1 being a side elevation, partly sectional, showing parts after discharge, and Fig. 2 parts in sectional side elevation ready for the discharge.

In the views, *a* indicates a dart, pea, shot, 40 or other loose missile usable when a target or object is aimed at, as in a parlor-game.

b is a plug chambered at its outer end to receive missile *a*. Usually the plug is all or partly cork and chamber *c* metal of any suitable shape, (that shown for a dart being conical,) with a tang or projection *d*, having an eye or the like *e* for the attachment of an

elastic or spring connection or cord *f*. Any manner of combination with plug *b* of chamber *c*, having eye *e*, may be used, providing 50 the plug fits air-tight. With *c* and *d* of metal any intelligent boy can when a cork plug is worn out or damaged cement or fix the parts *c d* in a new cork, and another advantage is that a cork plug lasts longer when relieved 55 of the strain of the cord during use, the strain coming upon the metal or strong material. The parts *b* to *e* are also made in one piece of rubber (or of vulcanite or hard material, with a rubber collar or the like) to fit air-tight in the muzzle of barrel *l*. A soft-rubber plug would be durable, yet harmless, even without tying it to the barrel, and as it could not be projected very far would be suitable in 60 rooms, where a more powerful projectile would 65 be prohibited; but there is no such restriction on the material or shape of the plug as to prevent its use as a more powerful projectile.

f is a rubber cord which will be stretched tight in the position of Fig. 2, so as to enable the plug to be drawn into engagement with the muzzle by retracting the piston-rod *m*.

g is a disk forming the head of a screw *i*, having an eye, hook, snap-hook, or the like 75 for attachment of an end of the elastic *f*. Any boy could suitably connect an elastic cord with the eyes or the like *h* if the cord *f* needed replacing.

j is a cupped leather or like washer, and *k* 80 a metal piston of sheet metal screwing into engagement with the piston-rod *m*, the screw *i* also screwing into the piston *k*. The parts *g* to *k* thus form a plunger which is extremely efficient for the purpose of compressing the 85 air between the cupped leather *j* and the plug *b* when the rod *m* is driven forward, which is done by pushing rapidly the handle *o*, to which the rod *m* is connected. Rod *m* is supported in suitable bearings, as *q*, at the rear of barrel 90 *l* and may carry a lubricating ring or rings *n*, of felt or other material, to facilitate the action of the plunger.

r is a lubricating-aperture in the barrel, and

p an aperture in the upper forward end of the hollow handle *o*, in which darts or missiles may be stored.

The escape of the air between the plunger 5 and the bearing *q*, which takes place when the plunger is retracted, is provided for in any suitable manner.

The barrel or tube *l* is not necessarily of equal diameter throughout.

10 It has been found that the noise of the explosion using this invention is so much greater than that of the common pop-gun that the amusement of hearing it is highly augmented.

15 The plug and its missile forming a duplex projectile is an important novelty, the missile *a* being easily discharged after a little practice into the bull's-eye of a target set at such a distance as would be convenient in a drawing room—say between five and ten yards. By 20 regarding the plug (or missile-socket) as a feature of the gun necessary to the discharge it may be said that at each discharge the said socket or plug leaves the gun and accompanies the missile during a portion of the flight 25 of the latter, which, encountering less air resistance, will travel a much greater distance.

What I claim as my invention, and desire to secure by Letters Patent of the United States, is—

30 1. In a toy gun, the combination of the barrel, a stopper adapted to close the open end thereof, a plunger adapted to reciprocate in said barrel, and a cord connecting said plunger and said stopper, said stopper being hol-

lowed out to form a chamber for the reception 35 of a dart or other missile, substantially as described.

2. In a toy gun, the combination of the barrel, a plunger working in said barrel and provided with an eyelet, a stopper adapted to close 40 one end of said barrel and provided with an eyelet, and an elastic cord secured at its ends in said eyelets, said stopper being recessed to form a chamber for the reception of a dart or other missile, substantially as described. 45

3. In a toy gun, the combination of the hollow barrel, a stopper adapted to close one end thereof, said stopper being provided with an eyelet, a piston provided with a cupped leather washer, means for fastening said washer to 50 said piston, said means being provided with an eyelet, an elastic cord connecting said eyelets, and means for operating said piston, substantially as described.

4. In a toy gun, the combination of a hollow 55 barrel, a piston adapted to reciprocate therein, a piston-rod attached to said piston, a hollow handle attached to said piston-rod, a stopper adapted to be inserted in one end of said gun-barrel, and an elastic cord connecting said 60 piston and said stopper, substantially as described.

In testimony whereof I affix my signature in presence of two witnesses.

FREDERICK GALE.
